(57) **CLAIM**

The ornamental design for a pleated and slit scarf, as shown and described.

DESCRIPTION

FIG. 1 is a top plan view of a pleated and slit scarf showing my new design, the bottom plan view being a mirror image thereof;

FIG. 2 is a front perspective view thereof; and,

FIG. 3 is a side perspective view in an alternate position thereof.

The broken line showing of the ends of the scarf and the stitching around the slit as well as the position and size of the broken lines relative to the claimed design and any other broken lines (such as on the mannequin illustrated in FIGS. 2 and 3) are to show the environment only (e.g., stitching) and are not part of the claimed design.
